ATTORNEY.

UNITED STATES PATENT OFFICE

132,360

DESIGN FOR A CARD RACK OR SIMILAR ARTICLE

Julius J. Gardner, New York, N. Y.

Application December 1, 1941, Serial No. 104,406

Term of patent 3½ years

To all whom it may concern:

Be it known that I, Julius J. Gardner, a citizen of the United States of America, residing in the Borough of Queens, county of Queens, and State of New York, have invented a new, original, and ornamental Design for a Card Rack or Similar Article, of which the following is a specification, reference being had to the accompanying drawing, forming part thereof,

Fig. 1 is a front perspective view of a card rack or similar article showing my new design.

Fig. 2 is a rear perspective view thereof.

I claim:

The ornamental design for a card rack or similar article, substantially as shown.

JULIUS J. GARDNER,
